CLAIM

The ornamental design for a safety pen needle, as shown and described.

DESCRIPTION

FIG. 1 is a first perspective view of a safety pen needle housing shield and pen needle showing a first embodiment of a new design of a safety pen needle;

FIG. 2 is a second perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and,

FIG. 8 is a bottom view thereof.

In the drawings, the broken lines illustrate portions of the article that form no part of the claimed design.
